UNITED STATES PATENT OFFICE.

JESSE T. STEWART, OF MABTON, WASHINGTON.

VENDING-MACHINE FOR ENVELOPS.

1,061,380.

Specification of Letters Patent. Patented May 13, 1913.

Application filed October 24, 1912. Serial No. 727,662.

To all whom it may concern:

Be it known that I, JESSE T. STEWART, a citizen of the United States, residing at Mabton, in the county of Yakima and State of Washington, have invented certain new and useful Improvements in Vending Machines for Envelops; and I do declare the following to be a full, clear, and exact description of the invention, such as will enable others skilled in the art to which it appertains to make and use the same.

This invention relates to vending machines, and more especially to those intended for selling stamped envelopes and the like; and the object of the same is to improve and yet to simplify the construction of a machine of this character and render it operable by the insertion of a nickel or other like coin.

To this end the invention consists in the construction of the vending mechanism proper, although in the following specification and in the drawings hereto attached I have described and shown one form of coin controlled mechanism to give a better idea of the operation of the whole. I wish it understood, however, that I lay no claim to the coin-controlled mechanism in this application, and reserve the right to use my vending mechanism in connection with any other check mechanism.

In the drawings:—Figure 1 is a perspective view of this device complete, showing the thumb piece as depressed and an envelope as being ejected from the casing. Figs. 2 and 3 are vertical sections on the lines 2—2 and 3—3 of Fig. 1, and Fig. 4 is a central vertical section of the machine complete. Fig. 5 is a transverse vertical section on the line 5—5 of Fig. 2. Figs. 6 and 7 are horizontal sections on the lines 6—6 and 7—7 of Fig. 2, respectively. Fig. 8 is a perspective detail of the ejector taken from the upper side, and Fig. 9 is a similar perspective detail of the ejector from its lower side. Fig. 10 is a perspective detail of the ejector lever, and Fig. 11 a perspective detail of the bracket in which said lever is hung. Fig. 12 is a perspective detail of the actuator for moving said lever. Fig. 13 is a perspective detail of the trip for actuating the trigger, and Fig. 14 is a collective perspective detail of the hanger for supporting the latch and the spring carried by said

hanger for raising said latch into normal engagement with the trigger.

The body of this device comprises a base 1 upon which is mounted a casing 2 composed preferably of glass panels at its sides and back and top, and open at its front; and removably inserted in said casing is a skeleton framework 3 which is secured fast to the back of the front panel 4 and which latter is held within and closes the open front of the casing by means of a lock 5 at the top and a lip 6 at the bottom engaging the base. It follows that when a key is inserted and the lock unlocked, the front 4 may be tilted forward and lifted upward to disengage its lip 6 from a notch 7 or other recess in the base, and then the entire internal mechanism can be withdrawn from the casing as for loading it with envelopes to be vended, oiling or repairing its machinery, or cleaning the inside of the casing; and afterward these parts are restored to the position illustrated in the various views of the drawings, and the machine set upon a table or other support in a public place. Here it becomes a tasteful article of furniture, ever ready to hand out a package of stationary to any one who will insert a nickel.

I prefer to put into a Government envelope containing a two-cent stamp, a sheet of letter paper or perhaps two sheets, and a postal card, and sell the package for five cents. The actual cost of the stamps being three cents and of the envelop and paper probably less than one cent, there is more than a penny profit to be divided between the owner and proprietor of the machine and the store-keeper who gives it space. The former will call daily or at periods, and replenish the depleted magazine and clean the machine, and the storekeeper will both make a small profit on every package of stationery sold and avoid the trouble of peddling out postage stamps and postal cards, while still not losing the advantage of the possible trade which this public convenience will draw to his store.

The skeleton framework 3 contains a magazine composed of an upright back 10 and side strips 11 coacting with the front panel 4, the top of this magazine being open for the reception of the envelop which rest normally upon its flat bottom 12

and is weighted down and fed to the ejector by a follower 13. It might be more accurate to say that the lowermost envelop rests upon an ejector 14 which is movable over the bottom 12, and the ejector consists of a flat plate having upturned lips 15 at its rear as seen in Fig. 8, and a handpiece 16 at its front end projecting through a slot 17 in the front panel 4 and turned downward at its extremity into a lip 18. The size of said slot 17 may be varied to suit the thickness of each envelop or package of stationery as above described, by setting a plate 19 which is secured to the inner face of the front panel by means of screws 20 as seen in Fig. 5, these screws passing through upright slots 21 in the plate in a manner which will be clear. As usual in machines for vending thin packages, this plate forms a stop for preventing any but the lowermost package from being ejected from the pile, and the upstanding lips 15 at the rear end of the ejector are made of a height equal to or less than the thickness of the lowermost package so that when the ejector is moved forward this package only is projected into the slot.

I provide the downturned lip 18 at the front end of the handpiece 16 for the purpose of preventing the ejector from moving too far to the rear, and also for giving the purchaser a good grip on said handpiece. The face plate 22 covering the slot on the exterior of the front pannel 4 will be provided with a suitable legend describing the use of the machine, and by preference this plate has an upward extension 23 as seen in Fig. 1 which is vertically slotted as at 24 for the passage of the shank of the thumb piece 25 forming part of the actuator yet to be described.

The actuator for the ejector comprises the mechanism which connects said thumb piece and the plate 14. Depending from the plate 45 14 is a bracket 30 constituting the trigger yet to be described and which projects through a slot 81 in the bottom of the magazine and is pierced with an eye 32 sliding on a rod 33 carried within the framework, 50 and on said rod is coiled an expansive spring 34 whose tendency is to move the bracket 30 and hence the ejector plate to the rear. Said bracket is provided with an ear 35 to which is pivoted one end of a link 36, 55 and the other end of this link is pivotally connected with the upper extremity 37 of the ejector lever best seen in Fig. 10. As therein shown, this lever comprises an upright arm 39 having an elbow 40 at its 60 lower end which merges into what might be called the body 41 of the lever, and a horizontal arm 42 projects from the other end of said body. This arm 42 and the elbow 40 have apertures through which 65 passes a pivot bolt 43, the same also pass-

ing through bearings 44 at the lower ends of the arms of a bracket 45 (see Fig. 11) of inverted U-shape which is secured beneath the bottom 12 of the magazine; and on this bolt is coiled a spring 46 having one end attached to the bracket and the other end to the lever, and whose tendency is to raise the thumb piece and the parts connecting it with the horizontal arm 42 of the lever 38—thus leaving the spring 34 to perform the sole function of sliding the ejector to the rear. Pivotally connected to the front end of said arm 42 is an upright link 46 (see Fig. 12) whose upper end is bent sharply forward into a finger 47 which projects through the upright slot 24 in the front of the casing and constitutes the shank of the thumb piece 25 above referred to. Said thumb piece by preference has its lower portion forked or slotted as at 48 so as to stand astride the front end of the finger 47, and a screw 49 may be passed through the fork-arms to attach the thumb piece thereto. Astride and around the rear end of the finger 49 is disposed a guide 50 having a U-shaped body removably secured to the finger by a screw 51, and the front ends of its arms are outturned into lips 52 spaced from the rear end of the fork-arms 48 just a sufficient distance to loosely embrace the front panel 4 of the casing and the upright extension 23 of the base plate 22. When these parts are to be removed, the screw 49 is withdrawn and the thumb piece slipped off the front end of the finger 47, after which the latter can be pushed inward through the slot 24 and disconnected from the ejector lever 38 if desired.

The action of the vending machine thus far described is as follows: The purchaser 105 depresses the thumb piece 25 whose shank moves downward in the slot 24, and, through the link 46, this depresses the horizontal arm 42 of the lever 38 which turns about the pivot bolt 43 so that its upright arm 39 110 moves forward and, through the link 36, carries the bracket 30 forward with it. Said bracket in its forward movement compresses the spring 34 and causes the ejector plate 14 115 to slide forward over the bottom of the magazine, and the upturned lips 15 at the rear end of this plate carry the lowermost package out of the stack contained within said magazine and projects it through the slot in the face plate 22. In the forward movement of the plate 14, its hand piece 16 is projected beyond said slot so that the purchaser may grasp the same and draw the plate still farther forward, in case the ejector should not project the envelop sufficiently far to permit him to grasp the front edge as shown in Fig. 1. Or he may hold the thumb piece 25 down with one hand 125 while he grasps the hand piece 16 with the other, and then removing his thumb from 130

the thumb piece he will use that hand to withdraw the envelop. Afterward the spring 34 restores the parts to their original position, the plate 14 and lips 15 sliding to the rear under the lowermost envelop in the stack and said lips finally engaging the rear end of said envelop preparatory for another action of the machine. The check-controlled mechanism for holding said ejector normally locked and releasing it on the insertion of a coin, may be—as suggested above—of any approved type, although I will describe what is shown in the drawings for illustrative purposes merely. A coin slot 60 in the front panel 4 of the casing leads through an upright chute 61, and at the lower end of said chute the coin falls against a trip plate 62 carried by the lower arm of a bell crank lever 63 which is pivoted at its angle at 64 to a suitable support. The rear arm of this lever is connected by a link 65 with a latch 66 which is pivoted between its ends in a hanger 67 (see Fig. 14) and has its inner end normally raised by a spring 68 which is secured to the lower end of said hanger by a clip plate 69 and a screw 70. The inner end of the latch 66 has a beveled lip 71 adapted to coact with the beveled lower end 72 of the bracket 30, which lower end constitutes the trigger, while the inner extremity of this end of the latch moves vertically in a slotted guide 73 as best seen in Fig. 5. Coiled on the rod 38 behind the trigger 30 is a starting spring 74 whose function is to move the ejector plate and trigger forward slightly as soon as the latter is disengaged by the latch, so that when the latch rises again it will not reengage the trigger; and it will be clear that if it were not for the presence of this starting spring the latch would play idly up and down forward of the trigger and the ejector could never be moved forward except at a time when this end of the latch was depressed.

The action of a coin mechanism of this character is as follows: A nickel being placed in the coin slot, travels down the chute and actuates the trip-lever 63, and the latter through the link 65 actuates the latch so that the inner end of the latch disengages the trigger; the starting spring 74 then moves the ejector 14 and trigger slightly forward, so that when the spring 68 returns the latch to its normal position its inner end stands behind instead of in front of the trigger. The starting forward of the ejector 14 projects the hand piece 16 at its front end and gives notice to the purchaser that he may then depress the thumb piece 25 to cause the machine to project an envelop through the slot 17. When his finger is slipped off said thumb piece, the spring 34 restores the ejector lever 38 to its proper position, and, through the link 36, 65 this moves the ejector plate 14 suddenly to

the rear with the assistance of the spring 34, so that the starting spring 74 is compressed slightly and the beveled end 72 of the trigger passes over the beveled lip 71 at the inner end of the latch to hold the ejecting mechanism housed within the casing.

It will be seen that the coin mechanism consists of the devices for permitting the insertion of a coin to actuate the latch, but that said latch is part of the vending mechanism because it is necessary to have it to hold the ejector housed, and as above suggested I do not limit myself to the use of any particular mechanism for moving said latch.

The sizes and materials and details of parts are obviously not essential.

What is claimed as new is:

1. In a vending machine, the combination with a base, and a transparent casing mounted thereon and open at its front, the base having a notch in its upper face at the bottom of said open front; of a front panel having a lip at its lower end adapted to engage said notch, a latch at the upper end of said panel, said panel having an opening for the delivery of the goods and an upright slot, a skeleton framework carried by the back of said panel and including a magazine whose bottom stands opposite said delivery opening, ejecting mechanism movable over said bottom, means for actuating said mechanism, and a thumb piece connected with said means and whose shank projects through said upright slot.

2. In a vending machine, the combination with a casing having an upright slot in its front panel, the vending mechanism, and the actuating mechanism therefor including an upright link having a finger projecting forward through said slot; of a thumb-piece standing forward of said panel and slotted to removably engage said finger, a screw passing through the thumb-piece and finger, a guide having a U-shaped body embracing the finger on the inner side of said front panel and upturned lips at the front ends of its arms, and means for securing said arms upon the finger.

3. In a vending machine, the combination with a casing having an upright slot in its front panel, the vending mechanism, and the actuating mechanism therefor including an upright link having a finger projecting forward through said slot; of a U-shaped guide whose body embraces said finger and whose arms are outturned at their front ends to slide against the inner face of said front panel at opposite sides of the slot therein, and a thumb-piece removably attached to the projecting end of said finger.

4. In a vending machine, the combination with a magazine, the ejecting mechanism, and a trigger thereon; of a hanger depend-

ing from an overhead support, a latch pivoted in said hanger, a spring for raising one end of the latch into normal engagement with said trigger, and a clip securing said 5 spring to the lower end of the hanger.

5. In a vending machine, the combination with an upright magazine having a slot in its bottom, an ejector plate movable over said bottom and having a trigger projecting 10 through said slot and provided with a beveled lower end, and a spring-actuating latch having a beveled lip normally engaging the beveled lower end of said trigger; of a spring forcing the ejector normally to the rear, and a starting spring acting on the ejector in the opposite direction, for the purpose set forth.

6. In a vending machine, the combination with an upright magazine having a slot in 20 its bottom, an ejector plate movable over said bottom and having a trigger projecting through said slot and provided with a beveled lower end, and a spring-actuating latch having a beveled lip normally engaging the 25 beveled lower end of said trigger, said trigger being pierced with an opening; of a rod fixed below said magazine and on which the opening in the trigger slides, a coiled ex-

pansive spring surrounding said rod forward of the trigger and bearing the latter 30 normally to the rear, and a coiled expansive starting spring surrounding the rod in rear of the trigger and acting thereon in the opposite direction, for the purpose set forth.

7. In a vending machine, the combination 35 with a magazine, a casing having a delivery opening in line with the bottom of said magazine, a follower within the latter adapted to rest upon the articles vended, an ejector slideable on said bottom, and a manually-operable actuator for said ejector; of a trigger projecting from the ejector and having a beveled tip, a spring pressing said trigger normally to the rear, a starting spring pressing the trigger in the opposite 45 direction, and a movable latch provided with a lip over which said beveled trigger moves when the ejector is returned to normal position within the magazine by its main spring.

In testimony whereof I have hereunto set 50 my hand in presence of two subscribing witnesses.

JESSE T. STEWART.
